UNITED STATES PATENT OFFICE.

PATRICK H. McCOOE, OF INDIANA HARBOR, INDIANA.

ANTICREEPER FOR RAILWAY-RAILS.

1,112,224.

Specification of Letters Patent. Patented Sept. 29, 1914.

Application filed November 6, 1913. Serial No. 799,469.

To all whom it may concern:

Be it known that I, PATRICK H. McCOOE, a citizen of the United States, residing at Indiana Harbor, in the county of Lake and State of Indiana, have invented a certain new and useful Improvement in Anticreeper for Railway-Rails, of which the following is a full, clear, concise, and exact description, reference being had to the accompanying drawings, forming a part of this specification.

My invention relates to railroad track equipment and has for its object the provision of improved devices for preventing the creepage of rails longitudinally of the track.

The general purposes of such devices is well known by those skilled in the art and many devices have been designed to accomplish such purpose, and I will not, therefore, set forth the broad advantage gained by the use of the device of my invention, the invention having for its own purpose the simplification of such devices and a construction thereof that will render them more practical.

The device of my invention includes two pieces which coöperate clampingly to engage the base flange of a rail section at the opposite longitudinal edges of the rail section, one of these pieces carrying a projection preferably integrally formed therewith that engages a vertical or upright face of a railroad tie and which extends beyond the general plane of the clamping portion toward the tie so as to afford clearance between the clamp proper and the tie. This projection or ear is disposed below the rail and at one side thereof and engages that face of the tie toward which creepage would occur were it not for the device of the invention, the invention being particularly adapted for service in double track systems in which each track is intended to be limited to traffic moving in one direction only. Because of the spacing intervening between the clamp of the structure and the railroad tie and on account of the location of the projection or lug carried by one of the two elements of the clamp at one side of the base flange of the rail, there can be no bodily longitudinal movement of the device of the invention along and with respect to the rail carrying the same since any movement of the rail toward the tie is accompanied by a turning movement or tendency to turning movement of the clamp in the plane of the rail base

whereby the rail base is grasped even tighter by the clamp thereby then more effectively to prevent creepage of the rail. The clamping structure is of such a nature that it will not loosen its hold upon the rail if the rail should move away from the tie.

I will explain my invention more fully by reference to the accompanying drawings showing the preferred embodiment thereof and in which—

Figure 1 is a view in cross sectional elevation of a track whose rails are equipped with the device of the invention; Fig. 2 is a detail view on a larger scale showing the relationship of the device of my invention to one of the rail sections and the tie as illustrated in Fig. 1; Fig. 3 is a side elevation of the parts shown in Fig. 2; Fig. 4 is a plan view of the parts shown in Figs. 2 and 3; Fig. 5 is a perspective view illustrating the device of the invention, the rail to which the device is applied and the tie against which the device abuts being cut away more clearly to reveal details of construction; Fig. 6 is a horizontal sectional view illustrating a detail of construction; and Fig. 7 is a perspective view illustrating one of the clamp members.

Like parts are indicated by similar characters of reference throughout the different figures.

In Fig. 1 I have shown two rail sections *a* of a railroad track which may be supported in any usual or preferred way upon a tie *b* which preserves the gage of the track and with respect to which tie track creepage is to be avoided. In some of the remaining figures the direction taken by the normal travel upon the track is indicated by arrows. The rails illustrated are of the usual type employing heads and base flanges that are united by vertical webs. The clamp of my invention includes one member whose intermediate portion *c* underlies the base flange *d* of the rail section *a* to which the device is applied, the portion *c* extending transversely of the rail (preferably at right angles thereto) and terminating at its ends in hooks *e* and *f* which extend upwardly and overlie, at their ends, the outer longitudinal edge portions of the base flange. The hook *e* is shaped snugly to receive one side of the base flange, as illustrated in Fig. 5, but the hook *f* is enlarged to receive not only the other side of the base flange but also the complementary clamp member *g* which is

desirably provided with upper and lower in-
setting lips, *h*, *i* to form a channel snugly
receiving the contiguous side of the base
flange. The top of the portion *c* leaves the
5 bottom surface of the flange *d* where the lip
i is disposed to afford space to receive such
lip. When the clamp member *g* is out of
position the space within the hook *f* that is
to receive the lip *h* and the upper portion of
10 the clamp member *g* in line with the lip *h*
permits the one piece clamp member *c*, *e*, *f*
to be located in position about the base
flange. The underlying lip *i* avoids any
tendency to shearing action between the con-
15 tiguous side of the base rail flange and the
underlying portion *c* and also takes part in
grasping the rail firmly. The portion of
the structure *g* which is disposed upon one
side of the base flange constitutes a clamp
20 member proper and tapers toward the tie
so as to constitute a wedge which will firmly
apply the hooks *e* and *f* respectively di-
rectly to the base flange and the clamp mem-
ber *g*, whereby the two clamp members are
25 held in very firm and fixed relation with the
base flange, the wall of the hook *f* that en-
gages the outer side of the member *g* being
preferably correspondingly tapered.

After the clamp member *g* has been
30 driven to position the flexible tongue *k* at
the smaller or front end of the clamp mem-
ber *g* is hammered back against the front
face of the hook *f* (as indicated in Fig. 5)
whereby the clamp member *g* cannot move
35 backwardly to loosen the engagement of the
clamp with the rail. The clamp portion *c*
is provided with a downwardly extending
projection or lug *l* which also extends for-
wardly of the clamp member into engage-
40 ment with the tie *b*. This projection or ear
l is desirably integrally formed with the
larger of the two clamp members and is lo-
cated to one side of the rail to which the
clamp is applied so as to turn or tend to
45 turn the clamp in the plane of the rail base
when the rail moves or tends to move toward
the tie. Spacing intervenes between the pro-
jection *l* and the base flange of the rail to
enable said projection to perform its func-
50 tion. If the rail should move or tend to
move in the reverse direction it is quite ap-
parent that the fixed relationship of the
clamp and rail would not be disturbed.

The top surface of the clamp element *c* is
55 rearwardly extended to afford an extended
foot *m*. A web *n* joins the central vertical
portion of the downwardly extending ear *l*
with the clamp element *c* and its rear ex-
60 tension *m* whereby the rail operates through
the foot *m* and the web *n* to prevent the ex-
tension *l* from bending to the rear when
the ear *l* is pressed against the tie, the mate-
rial of which the structure is made being
65 preferably malleable cast iron. By means
of the foot *m* and web *n* the clamp member *c*

is maintained in exact parallelism with the
base flange of the rail so that hooks *e* and *f*
do not turn in vertical planes. Further to
strengthen the structure a rib *o* extends un-
derneath the clamp member *c* and about the
70 exteriors of the hooks *e* and *f*, this rib being
cast integrally with the said clamp member
and its hooks. The hook *e* is desirably pro-
vided with an additional rib *p* further to
strengthen it. The ribs *o* and *p* are merged
75 in one casting with the web *n* whereby the
web and ribs reinforce each other.

While I have herein shown and particu-
larly described the preferred embodiment of
my invention I do not wish to be limited to
80 the precise details of description shown as
changes may readily be made without de-
parting from the spirit of the invention,
but—

Having thus described my invention I 85
claim as new and desire to secure by Letters
Patent the following:—

1. An anticreeper for railway rails in-
cluding two single piece clamp members, one
underlying the base flange of a rail and ter-
minating in hooks *e* *f* which themselves
90 terminate above and overlie the base flange
and which hooks are spaced apart for re-
ceiving the base flange therebetween, hook *e*
being adapted to receive one side of the 95
flange, the space of the second hook *f* afford-
ing clearance between the upper end of this
latter hook and the top of the base flange
for purpose of assembly, also clearance be-
tween the adjacent side of the base flange
100 and this latter hook to receive the second
clamp member, the second clamp member *g*
being provided with an insetting lip *h* which
overlies said adjacent side of the base flange,
said second clamp member being tapered in
105 the direction in which creepage of the rail is
to be guarded against; a downwardly ex-
tending ear *l* carried by the clamp and
which extends forwardly of the clamp in
position to engage a tie and to space the tie 110
from the clamp, said ear being located at
one side of the clamp and with spacing be-
tween said ear and the base flange of the
rail to enable turning effort to be exerted
upon the clamp when the rail is moved to-
ward the tie, the first clamp member being
rearwardly extended beyond its hook *e* to af-
ford an extended foot *m*, and a brace *n*
joining a central vertical portion of the ear
l with the foot *m* to prevent the ear *l* from 120
bending to the rear when the ear is pressed
against the tie.

2. An anticreeper for railway rails in-
cluding two single piece clamp members, one
underlying the base flange of a rail and ter-
minating in hooks *e* *f* which themselves ter-
minate above the base flange and which
hooks are spaced apart for receiving the base
flange therebetween, hook *e* being adapted
to receive one side of the flange, the space of 130

hook *f* receiving the second clamp member between the adjacent side of the rail base and hook *f*, this second clamp member being tapered in the direction in which the creepage of the rail is to be guarded against; a 5 downwardly extending ear carried by the clamp at and below hook *e* and which extends forwardly of the clamp, said ear being located at one side of the clamp with spacing between it and the base flange of the rail to enable turning effort to be exerted upon the clamp when the rail is moved toward the tie, the first clamp member being 10

rearwardly extended at and beyond the hook *e* to constitute an extended foot *m*, and a 15 brace *n* joining the lower portion of said ear with said foot to oppose the bending of the ear to the rear when the ear is pressed against the tie.

In witness whereof, I hereunto subscribe 20 my name this thirtieth day of October A. D., 1913.

PATRICK H. McCOOE.
